By his Attorney, Fred F. Schuerk

UNITED STATES PATENT OFFICE.

WILLIAM A. LINDENFELSER, OF NEW YORK, N. Y.

ADHESIVE-APPLYING APPARATUS.

1,000,096.

Specification of Letters Patent. Patented Aug. 8, 1911.

Application filed February 8, 1909. Serial No. 476,706.

To all whom it may concern:

Be it known that I, WILLIAM A. LINDENFELSER, a citizen of the United States, and a resident of Ozone Park, borough of 5 Queens, city of New York, in the county of Queens and State of New York, have invented certain new and useful Improvements in Adhesive-Applying Apparatus, of which the following is a specification.

10 My invention relates to an apparatus for applying adhesives such as mucilage, glue, gum, and paste to paper and the like.

It has for its object to automatically feed the paper to an adhesive supplying surface, 15 completely coat same and to automatically remove the said paper therefrom, and in such a manner that no adhesive reaches the unexposed side of subsequent papers; also, to construct the apparatus such that the 20 various parts are readily accessible, and the adhesive supplying surface removable.

The nature of my invention will be best understood in connection with the accompanying drawings in which—

25 Figure 1 is a front elevation of the improved apparatus with a portion of the mechanism broken away. Fig. 2 is a side elevation. Fig. 3 is a detail view illustrating the action of the apparatus.

30 Similar characters of reference designate corresponding parts throughout the several views.

Referring now to the drawings, 10 designates a supporting frame in which is cast 35 an adhesive container 11 open at the top, except at the front where it is closed by a feed plate 12. The sides of the container 11 are notched to receive a shaft 13 carrying the adhesive supplying roll 14 which dips 40 into said container. A wiping plate 15 is suitably supported within said container to remove the superfluous adhesive from the roll 14.

Upon the shaft 13 is mounted a drying 45 gear 16 adapted to be rotated by a crank 17, and is locked against return movement by a spring pressed pawl 18. Pivotedly connected to the sides of the frame 10, at one end, are two upright plates 19 of a casing containing 50 the paper feeding and take-off mechanism.

This casing is adapted to fit upon the top of the frame 10, and may be locked to the sides of same by means of suitable hooks 20.

55 Shafts 21, 22, and 23 are supported by the plates 19 and carry corresponding rolls 24, 25 and 26, as well as gear wheels 27, 28

and 29. The bearings of these shafts may be slotted to allow for various thickness of paper. A rod 30 is also mounted in these plates and carries a number of fingers 31 60 which rest at various points along the surface of the adhesive supplying roll 14, the required pressure being provided by means of a spring 32 acting upon the rod 30. These fingers are shaped to direct the paper 65 33 in the proper direction, as will herein-after be more fully explained.

A number of transverse grooves 34 are cut into the roll 25, and the roll 26 is provided with a number of friction disks 35 70 adapted to register with the said grooves 34.

The operation of my apparatus is as follows: The paper 33 is placed upon the feed plate 12 and brought under the roll 24. In turning the crank 17, the surface of the 75 adhesive supplying roll 14 carries sufficient adhesive up from the container 11, and rotates the said roll 24, through gear wheels 16 and 27, the two rolls co-acting to feed the paper 33 forward and at the same time 80 to force it against the adhesive coated surface of the roll 14, thereby coating the said paper. By the time the paper strikes the roll 25, which is likewise driven from roll 14, through gears 16 and 28, it has a tendency to curl backwardly due to the moisture received from the adhesive, and is assisted in its removal by the motion of the said roll 25 as well as by the fingers 31. These fingers lift the same from off the surface of 90 the roll 14, and guide and direct it between the roll 25 and the take-off roll 26 whose friction disks 35 make contact with the said paper, tending to forcibly withdraw it from the surface of the roll 14.

As the friction disks 35 come in contact with the coated surface of the paper, which has been exposed to the adhesive, they naturally will retain some of said adhesive. This adhesive, however, is not communicated to the roll 25, and thereby to the unexposed side of subsequent papers, since the 100 grooves 34 are provided, and register with the said friction disks 35.

If it be desired to remove the adhesive 105 from the container 11, as well as to clean the roll 14 and other parts of the mechanism, the entire upper part of the apparatus may be lifted off by unhooking the hooks 20, whereupon the roll 14 may be 110 lifted out and the container 11 will be readily accessible.

I claim:

1. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear, and a take-off roll coacting therewith. 35
5. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear and provided with a number of transverse grooves; and a take-off roll carrying a number of friction disks registering with the said grooves. 40
10. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear; a take-off roll coacting therewith; and means to guide the paper from said adhesive applying roll. 45
15. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear; a take-off roll coacting therewith; and means to guide the paper from said adhesive applying roll. 50
20. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear; a take-off roll coacting therewith; and a number of spring pressed fingers intermediate of said friction disks and resting upon the adhesive applying roll to guide the paper from the same. 55
25. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear; a take-off roll coacting therewith; and a number of spring pressed fingers resting upon said adhesive applying roll to guide the paper from same. 60
30. In an adhesive applying machine: an adhesive container; an adhesive applying roll; a driving gear and crank on said roll; a roll driven by said gear and coacting with said adhesive applying roll to feed paper or the like thereto; a second roll driven by

said driving gear and provided with a number of transverse grooves; and a take-off roll carrying a number of friction disks registering with the said grooves. 35

5. In an adhesive applying machine: an adhesive container; an adhesive applying roll; a driving gear and a crank on said roll; a roll driven by said gear and coacting with said adhesive applying roll to feed paper or the like thereto; a second roll driven by said driving gear and provided with a number of transverse grooves, a take-off roll driven by said latter roll and carrying a number of friction disks registering with the said grooves; and a number of spring pressed fingers intermediate of said friction disks and resting upon the adhesive applying roll to guide the paper from the same. 40

6. In a machine of the character set forth: take-off mechanism comprising a roll provided with suitable peripheral grooves, a second roll carrying a number of friction disks registering with the said grooves, and means to rotate the said rolls, whereby the coating applied to the material is not transferred from said disks to the said first roll. 45

Signed at New York in the county of New York and State of New York this 5th day of February A. D. 1909.

WILLIAM A. LINDENFELSER.
